UNITED STATES PATENT OFFICE.

WARREN H. BARSTOW, OF TOPPENISH, WASHINGTON.

ROTARY STEAM-ENGINE.

1,310,735.

Specification of Letters Patent. Patented July 22, 1919.

Application filed November 26, 1918. Serial No. 264,449.

To all whom it may concern:

Be it known that I, WARREN H. BARSTOW, a citizen of the United States, residing at Toppenish, in the county of Yakima and 5 State of Washington, have invented a new and useful Improvement in Rotary Steam-Engines, of which the following is a specification.

This invention relates to improvements 10 in rotary steam engines, and more particularly to improvements on my prior co-pending application for rotary steam engines, and the object of this improvement is to provide steam actuated inlet valves for sup- 15 plying steam at the proper intervals between abutments of each rotor and sliding cut-off used in conjunction therewith, also to provide novel means for operating the sliding cut-offs at the proper period to allow 20 the rotor abutments clear passage in their respective chambers.

A further object is to provide the rotors and the steam chests in the same horizontal plane and to have all actuating valves movable horizontally instead of vertically.

A still further object resides in the simplicity of construction and comparatively low installation cost, yet embodying positiveness and reliability in operation. 30 The invention consists in the adaptation and combination of parts as will be more fully described in the following specification, illustrated in the accompanying drawings, and finally pointed out in the appended 35 claim.

In the drawings, Figure 1 is a front elevation of an engine embodying the invention; Fig. 2 is a horizontal section of the same; Fig. 3 is an elevation of one of the steam 40 chests, showing means for supplying steam at the proper intervals to the rotor with which it is connected; Fig. 4 is a sectional end elevation of the same, on line 4—4 of Fig. 3; Fig. 5 is a detail of one of the actuating rods for the sliding valve connected with the cam upon the drive shaft of the rotors; Fig. 6 is an elevation of one of the rotors and the actuating valve mechanism for supplying steam thereto; and Fig. 7 is 45 a section of a standard steam actuating sliding valve.

Referring more particularly to the drawings, in which like reference numerals indicate like parts, the numeral 1 comprises a 50 base having upright supports 2 and provided with bearings 3 for the rotary engine

shaft 4 and disposed upon this engine shaft by being keyed thereto are a plurality of rotors 5 within a casing 6 secured to the base 1 in any well known manner.

This casing is formed with two independent expansion chambers 7 separated from each other by an intervening wall 8 and closed at their outer sides by heads 9 rigidly secured thereto. Within each of the expansion chambers 7 is a rotor 5 having a fixed abutment 10, the outer edge of which moves in contact with the periphery 11 of the expansion chamber, the periphery 12 of the rotor forming the inner wall of the expansion chamber, as shown in Fig. 6.

Located preferably at the side of the casing 6 are extension chambers 13 in alignment with the chambers 7 to receive sliding cut-offs 14 and these cut-offs are actuated by slide valves 15, to which they are attached by piston 16, the valves being disposed within the cylinders 17 of standard type, having alternate exit and inlet ports 18 and 19 for steam to reciprocate the valves 15. The reception of steam into these ports being controlled by the cam rods 20 attached to slide valves 21 within steam chests 22 receiving steam directly from a steam pipe 40, the cam rods 20 being bifurcated at their other ends and having inwardly directed pintles slidably engageable with cam slots 23 provided around the outer periphery of rotor disks 24 keyed to the shaft 4. These cam slots are so arranged with respect to the cam rods 20 that the off-set portions thereof act first on one of said rods and then on the other, thereby alternately shifting the slide valves 15 for the purpose of admitting steam alternately to the cylinders 17 to actuate the sliding cut-offs 14.

Stationarily disposed upon stuffing boxes 25 in contact with the shaft 4 on both sides of the casing 6 that house the rotors 5 are the steam chests 26 for supplying steam to the respective rotor chambers.

Within these steam chests 26 are provided rotor disks 27 keyed to the shaft 4 and having provided near their outer periphery circular shaped steam passage ports 28. 29 are similar shaped disks mounted upon the shaft 4 in abutting contact with the disks 27 and are adapted to be rotatably shifted by threaded pinions 30 attached thereto and actuated by manually operated wheels 31.

The disks 29 are each respectively provided with two sets of inlet ports 32 and 33

and a longitudinal slot for the exhaust steam, the respective ends thereof being designated by numerals 32' and 33' respectively to associate their positions with respect 5 to the exhaust pipes 35' when the disks 29 are shifted. Each of the inlet ports above referred to is in alinement with the circular shaped steam passage ports 28 of the disks 27, the ports 33 being adapted to be centered 10 over the inlet pipes 35 leading from the casing of the steam chests 26 to the rotor chambers 7 for admitting steam to actuate the rotors, whereas the ports 32 are adapted to be centered over the exhaust pipes 35' cor- 15 respondingly leading from the casing of the steam chests 26 to the rotor chambers 7 for normally expelling the exhaust steam from the rotor chambers. Each of the exhaust ports 32' and 33' of the longitudinal slot are 20 adapted to be centered alternately over the common exhaust pipe 34 by the shifting of the disks 29 for liberating the exhaust from the rotor chambers to the atmosphere. It is obvious that by shifting the disks 29 to the 25 position shown in Fig. 3 the exhaust from the rotor chambers is expelled through the normal exhaust pipe 35' into the exhaust port 32' of the slot and passes outwardly through the other exhaust port 33' of the slot 30 into the common exhaust pipe 34 over which it is centered. By shifting the disks 29 to the right the position of the exhaust ports of the slot are transposed centering the ex- 35 haust port 33' over the former intake pipe 35 and the exhaust port 32' over the common exhaust pipe 34, hence reversing the course of steam supply to the rotor chambers by centering the normally dormant intake steam ports 32 over the former exhaust ports 35' 40 thereby directing the exhaust from the rotor chambers through the former intake pipes 35 from whence it is expelled through the exhaust ports 33' of the longitudinal slots to the common exhaust pipe 34 into the at- 45 mosphere.

The rotor disks 27 are correspondingly arranged with respect to the cam slots 23 that control the cut-offs 14, so that the circular shaped steam inlet ports for admitting 50 steam into the rotor chambers at predetermined intervals are timed to act synchronously.

The mechanism for operating the sliding cut-offs will now be described as follows: 55 The wheels 31 which control the forward and reverse speeds of the engine will be properly set. As illustrated in Figs. 3 and 4, steam is shown admitted from the respective steam chests 26 through the circular shaped inlet ports 28 of the rotor disks 27 and is escaping through the ports 33 of the disks 29 into the steam pipes 35 from which it is expelled into the chambers 7 of the rotors where it impinges against the abut- 60 ments 10 and actuates the rotors in a for-

ward direction. As soon as the disks 27 have rotated to the point where the circular shaped steam inlet ports 28 have passed their entire length over the ports 33 of the disks 29, the slotted camways 23 will have actuated the 70 sliding valves 21 to admit steam into the cylinders 17 and actuate the piston heads thereof to raise the sliding cut-offs from their abutting contact with the rotors 5, thus permitting the abutments 10 which have 75 passed around to the position shown by dotted lines to continue in rotation, steam having been cut off from this particular chamber herein shown by the momentary closing of the port 33 by the solid section of the disk 80 27 passing thereover.

It is to be understood that the abutments of the two rotors are arranged diametrically opposite so that steam is admitted through one of the ports to the space between one 85 of the cut-offs and the respective abutment, and after one-half of the revolution has taken place, steam is admitted between the other cut-off and the abutment of the respective rotor. During the time that an abutment is passing a cut-off, the respective slide valve is moved to a closed position while in the other expansion chamber, the steam is acting under full pressure between the re- 90 spective cut-off and abutment. 95

In order to drive the engine in the opposite direction, the wheels 31 are actuated so as to shift the disks 29, causing the previous intake ports 33 and exhaust ports 33' to be out of alinement with the steam intake and 100 exhaust pipes 35 and 35' and in place thereof of the intake ports 32 with their companion exhaust ports 32' are now brought into alinement, whereupon steam is admitted into the rotor chambers through the former exhaust 105 pipes 35', which now become the intake ports and the former intake pipes 35 now become the exhaust ports.

It is to be understood that changes in the details of construction can be made within 110 the scope of the following claim.

What I claim as new, and desire to protect by Letters Patent, is:—

In a rotary steam engine the combination 115 of a stationary casing comprising separate and independent annular expansion chambers, a rotatably mounted shaft extending through said chambers, rotors fixedly secured to said shaft and operable within said chambers, being respectively provided with 120 a radially extended abutment diametrically opposite each other, radially slidable cut-offs movable across said chambers and ar- 125 ranged in transverse alinement with each other, steam actuated pistons attached re- spectively to said cut-offs, cylinders for said pistons, cam disks carried by said shaft, levers attached slidably to said cams and to the sliding valves of the cylinders for con- 130 trolling the intake and cut-off of steam

thereto for reciprocating said cut-offs, steam chests stationarily mounted upon said shaft on both sides of said casing, a shiftably and a rotatably mounted disk disposed in each of said steam chests, steam outlet and exhaust pipes leading from said steam chests to each of said rotor chambers for supplying steam thereto to actuate said rotors, crescent shaped slots provided respectively in each of said rotatably mounted disks for limiting the passage of steam from said chests to one of said steam outlet pipes during a predetermined part of each revolution, a longitudinal slot provided in each of said shiftably mounted disks for direct-

ing the exhaust expelled from the rotor chambers to the atmosphere, and a plurality of ports provided in each of said shiftably mounted disks for preselecting the ports of the steam outlet pipes through which steam is permitted to pass from said chests to the rotor chambers, thereby predetermining the direction of rotation of said engine. 20

Signed by me at Seattle, Washington, this 5th day of Nov., 1918.

WARREN H. BARSTOW.
